UNITED STATES PATENT OFFICE

MATTHEW GRESAK, OF DU BOIS, PENNSYLVANIA

EXTENSIBLE WINDOW SCREEN

Application filed February 4, 1929. Serial No. 337,394.

This invention relates to extensible window screens and has for an object to provide a screen embodying a rigid body part with laterally slidable parts controlled simultaneously and positively by manual means.

A further object of the invention is to provide an extensible screen comprising a central rigid body part with laterally slidable edge marginal members with means carried by the body part for the application of manual stress translated into driving force for moving the movable members laterally.

A further object of the invention is to provide a window screen composed of a rigidly organized central body portion having side members laterally movable relative thereto for engagement with the window frame and with manual means for moving the laterally movable part in constant parallelism with each other and with the sides of the body portion of the screen.

With these and other objects in view, the invention comprises certain novel parts, elements, units, combinations, constructions, interactions, functions and mechanical movements as will be hereinafter more fully described and claimed.

In the drawings:

Figure 1 is a view of the improved screen 30 with binding strips removed, disclosing the internal construction.

Figure 2 is a transverse sectional view taken on line 2—2 of Figure 1.

Figure 3 is a vertical transverse sectional view taken on line 3—3 of Figure 1.

Figure 4 is a transverse sectional view taken on line 4—4 of Figure 1.

Figure 5 is a view of the screen in elevation as seen from the exterior.

Figure 6 is an inverted plan view of the screen.

Figure 7 is a detail elevation of the lock.

Like characters of reference indicate corresponding parts throughout the several views.

The improved screen which forms the subject matter of this application comprises a central rigid body member A filled as usual with wire or other fabric and with laterally slidable members B and C.

The body portion A is made up in substantially the usual and ordinary manner with a frame 10 and strips 11, the latter being preferably employed for holding the fabric 12 in proper organization with the body structure and also in combination with the rabbits 13 of the body part forming guideways for the sliding members B and C.

The sliding members B and C comprise tongues 14 slidable in the guideways with face members 15, here shown as being secured to the tongue members 14 by screws 16, although it is to be understood that the manner of constructing the sliding members whether integral or in combined parts is no limitation upon the present invention.

One of the horizontal bars of the body part, which may be considered for descriptive purposes the bottom rail, is channeled out as at 17 and 18 to accommodate links 19 and 20 which are connected at their outer ends to the sliding members B and C by having their ends formed into hooks or right angled bends 21 and 22 and engaged into the tongue 14 of the sliding members.

The proximate ends of the links 19 and 20 are connected to a lever 23 upon opposite sides of the rod 24 which forms a fulcrum for said lever 23 so that, as said lever 23 is manually moved from full line to dotted line position as shown at Figure 2, the tendency is to move the sliding members B and C from full line to dotted line positions.

However, this connection as above described connects only at that part of the structure referred to as the bottom and for operating the upper ends of the sliding members B and C, a similar construction is provided in a crosshead 25 rigidly carried adjacent the upper end of the rod 24 and pivotally connected with the links 26 and 27, the construction and spacing of said upper part being similar in all respects to the lower part represented by the lever 23 so that, as the lever 23 is actuated oscillating the rod 24, the crosshead 25 is likewise oscillated so that the links 26 and 27 are actuated in the same manner as the links 18 and 19 to simultaneously and similarly actuate the upper ends of the sliding strips B and C so that the result is an inverted plan view of the screen.

accurate parallel movement of the strips B and C relative to each other and to the body portion A.

For further stabilizing the parts, dowels 28 and sockets 29 form guides between the sliding members B and C and the body A.

To maintain the sliding parts B and C in extended or frame engaging position, a latch is provided comprising a resilient member

10 which may be termed a wire 30 secured to the frame 10 by forming reverse bends as at 31 in which are seated screws 32 with a keeper

33. An offset 34 is formed in the wire 30 continued by an inclined part 35 so that, as

15 the lever 23 moves from full line to dotted position, as shown at Figure 2, the lever will ride up the inclined part 35 and by the resiliency of the part 30 be engaged back of the offset 34 and retained in locked position.

20 The upturned extremity 36 is provided for convenience in releasing the latch from locking engagement.

In operation, the screen with the sliding parts B and C retracted as shown at Figure

25 2 and of the proper size will be inserted into the window opening and the lever 23 manually moved from full line position to dotted position, which will extend the sliding parts B and C to dotted line position so that the

30 sliding parts B and C will engage the window frame, as shown at Figure 5. When in such engaging position, the parts will be locked in such relation by the engagement of the lock, shown at Figures 6 and 7, with the

35 lever 23, which locking engagement is releasable manually by engagement of the finger or thumb with the upturned extremity 36 of the latch. Releasing the lever and reversing the movement of such lever again retracts the sliding parts B and C so that it may be readily removed from the window opening.

It is well known that in modern practice, the sizes of windows have been standardized to a great extent and that in the major part of building constructions at the present time "stock sizes" of windows are ordinarily employed. These stock sizes are not numerous and the window screens of the present construction can readily be made to conform to such stock sizes and can, therefore, be fabricated at the factory and sold to fit the major portion of the window openings as at present employed. This will largely save the cost of individual screen construction for separate windows.

What I claim to be new is:

1. A window screen comprising a body part, marginal parts mounted to slide laterally relative to the body part, a rod extending across the body part in parallelism with the sliding parts, a lever connected with the rod, and links actuated by the oscillation of the rod for sliding the sliding parts in simultaneous parallelism.
2. A window screen comprising a body part, marginal parts mounted to slide laterally relative to the body part, a rod mounted to oscillate and extending across the body part in parallelism with the sliding parts, cross-heads mounted upon the rod, one of which is extended to form a lever, and links pivoted to the crossheads and extending to and connected with the sliding parts.
3. A window screen comprising a body part, laterally slideable marginal parts, a rod journaled to oscillate and extending across the body part in parallelism with the sliding parts, crossheads mounted rigidly upon the rod, one of which is extended to form a lever, links pivoted to the crossheads and extending to and connected with the sliding parts, and a latch carried by the body part positioned to engage and restrain the lever.

In testimony whereof I affix my signature. 85
MATTHEW GRESAK.
